(57) **CLAIM**

The ornamental design for a TV on a sliding door, as shown and described.

DESCRIPTION

FIG. 1 is a perspective view of a TV on a sliding door in accordance with the principles of the present design;

FIG. 2 is a front view of the TV on a sliding door of FIG. 1;

FIG. 3 is a top view of the TV on a sliding door of FIG. 1; and,

FIG. 4 is a side view of the TV on a sliding door of FIG. 1. In the drawings, the broken lines depict environmental subject matter only and form no part of the claimed design.
